UNITED STATES PATENT OFFICE.

FRANK HUBACEK, OF CRISP, TEXAS.

RAILROAD-CROSSING SIGNAL.

Application filed February 21, 1924. Serial No. 694,289.

To all whom it may concern:

Be it known that I, FRANK HUBACEK, a citizen of the United States of America, residing at Crisp, in the county of Ellis and 5 State of Texas, have invented certain new and useful Improvements in Railroad-Crossing Signals, of which the following is a specification.

This invention relates to certain new and 10 useful improvements in railroad crossing signals and particularly to the type of signal that is automatically operated by the wheels of rolling stock passing over trip devices for both sounding an alarm and 15 waving a flag.

The primary object of the invention is to provide a railroad crossing signal wherein a post or stand located adjacent a railroad crossover, supports a bell and a flag staff 20 pivotally mounted thereto at one end with operating means for the bell and flag staff including trip devices arranged adjacent a track rail for sounding the bell and waving the flag.

25 With the above and other objects in view that will become apparent during the course of the following description, it is nevertheless to be understood that minor changes may be made therein without departing 30 from the spirit and scope of the invention as claimed.

In the drawings, wherein like reference characters designate corresponding parts throughout the several views,

35 Figure 1 is a side elevational view of a railroad track equipped with the crossing signal apparatus forming the subject matter of the present invention,

40 Figure 2 is a top plan view of the track and signal apparatus,

Figure 3 is an enlarged side elevational view of the track showing the trip devices for operating the signal mechanism,

45 Figure 4 is a fragmentary top plan view of the track and the signal apparatus associated therewith,

50 Figure 5 is a cross-sectional view taken on line V—V of Fig. 4 showing the trip operated lever having link connections with a bell hammer and a flag staff,

Figure 6 is an end elevational view showing the post adjacent the cross-over supporting the bell and flag and the operating means therefor,

55 Figure 7 is a detail sectional view taken on line VII—VII of Fig. 6,

Figure 8 is a side elevational view of the signal post,

Figure 9 is an enlarged detail side elevational view of a portion of the track rail 60 showing the trip device at the end of a series; and

Figure 10 is a detail sectional view taken on line X—X of Fig. 9.

Referring more in detail to the accompanying drawings, there is illustrated a railroad crossing signal, the railroad being represented by the ties 1 supporting track rails 2 that traverse the cross-over 3 as shown in Figs. 1 and 2. The tie 1^a adjacent the cross-over 3 extends a considerable distance outwardly of the adjacent rail 2 and terminates in proximity of the adjacent end of the cross-over and has secured thereto a perpendicular signal supporting post 4. The signals supported upon the post 4 include a bell 5 and a flag 6 carried by the shaft 7 that is pivotally mounted as at 8 adjacent the upper end of the signal post 4.

The operating means for the bell and flag include a plurality of trip devices arranged adjacent one of the rails 2 and having operative connections with the bell and flag staff, the trip devices being in the form of levers 9 pivotally mounted at 10 to the outer side of the rail 2, each trip lever 9 carrying an eyelet 11 adjacent the pivot point 10 and an eyelet 12 at its forward end and through which eyelets, a flexible cable 13 freely extends. The cable 13 in passing through the end trip lever 9 positioned the greatest distance from the signal post 4 is directed downwardly as shown in detail in Fig. 9 and is anchored to the bracket 14 secured to the tie 1. The connection between the end cable 13 and bracket 14 includes a screw eye bolt 15 for tightening the cable and removing slack therefrom.

A bell crank lever 16 as shown in Fig. 4 is pivotally supported on the tie 1^a outwardly of the rail 2 and has the adjacent end of the cable 13 attached to the leg 17 thereof. The other leg 18 has one end of a coil spring 19 attached thereto with the outer end of the spring anchored as at 20 to the tie 1^a 105 for normally holding the bell crank lever under tension with the cable 13 drawn to a taut condition.

As shown in Fig. 6, a bracket 21 supported upon the outer end of the tie 1^a has a lever 22 pivotally mounted thereon as at 23, a link 24 being connected at one of its ends to the

offset portion 25 of the lever 22 at the point 26 while the other end of said link is connected as at 27 to the outer end of the bell crank lever 18. The lever 22 has a link connection 28 intermediate the ends thereof with the flag staff 7 and a link 29 connected at one end to the outer end of the lever 22 is attached at its other end to the bell hammer 30 that is pivotally mounted as at 31 upon 10 the post 4 adjacent the bell 5. In the normal position of the mechanism, the spring 19 holds the bell crank lever 18 under tension and the link connection 24 between the bell crank and lever 22 holds the lever 22 at its 15 limit of downward movement with the flag staff 7 lowered and the bell hammer 30 elevated at its striking end. When the wheels of rolling stock pass over the trip levers 9, the same are successively moved upon their 20 pivot points 10 with the forward ends of the trip levers 9 lowering or pulling upon the cable 13 to shift the bell crank lever 18 and elevate the lever 22 for raising the flag staff 7 and causing the hammer 30 to strike the 25 bell 5. The car wheels will successively operate the trip levers 9 and cause the flag to be waved and an intermittent striking or sounding of the bell.

While there is herein shown and described 30 the preferred embodiment of the present invention, it is nevertheless to be understood that minor changes may be made therein without departing from the spirit and scope of the invention as claimed.

35 What is claimed as new is:—

1. In a railroad crossing signal, a signal

post, a bell on the post with a hammer adjacent the same, a flag staff pivoted on the post, means associated with the bell hammer and flag staff and operated by the wheels of 40 rolling stock for ringing the bell and swinging the flag staff, said means including a lever pivotally mounted at one end and having a link connection with the bell hammer at its outer free end and an intermediate link connection with the flag staff, a bell crank lever having a link connection with the aforesaid lever, a cable connected to the bell crank and extending along a track rail, and spaced wheel engaging trip devices 45 50 for operating the cable.

2. In a railroad crossing signal, a signal post, a bell on the post with a hammer adjacent the same, a flag staff pivoted on the post, means associated with the bell hammer and flag staff and operated by the wheels of 55 rolling stock for ringing the bell and swinging the flag staff, said means including a lever pivotally mounted at one end and having a link connection with the bell hammer at its outer free end and an intermediate link connection with the flag staff, an offset carried by the lever adjacent its pivot point, a bell crank lever having a link 60 connection with the offset portion of the aforesaid lever, a cable connected to the bell crank and extending along a track rail, and trip levers associated with the cable and operated by the wheels of rolling stock.

In testimony whereof I affix my signature.

FRANK HUBACEK.
